UNITED STATES PATENT OFFICE.

JOHN FARMER, OF ARGENTA, AND MARK E. SHERLAND, OF McGEHEE, ARKANSAS.

STEAM-BOILER CONSTRUCTION.

1,134,115.

Specification of Letters Patent.

Patented Apr. 6, 1915.

Application filed June 16, 1914. Serial No. 845,363.

To all whom it may concern:

Be it known that we, JOHN FARMER and MARK E. SHERLAND, citizens of the United States of America, residing at, respectively, 5 Argenta, county of Pulaski, State of Arkansas, and McGehee, county of Desha, and State of Arkansas, have invented certain new and useful Improvements in Steam-Boiler Construction, of which the following 10 is a specification.

The present invention relates to improvements in steam boiler construction, and is especially adapted for use in connection with tubular steam boilers and preferably of a 15 locomotive type.

The primary object of the invention is to improve and provide a novel construction at the front end of the steam boiler in the construction and arrangement of the front 20 flue sheet, with the purpose or object in view of converting a standard type locomotive for use with our invention, without encroaching upon the space usually allotted to the fire tubes, at comparatively inexpensive 25 cost.

A further object of our invention is to simplify the construction of a locomotive boiler at the smoke box end thereof, by eliminating the steam pipes which lead to the 30 cylinders, from the smoke box, and thus leaving the smoke box open and unobstructed for the clear passage of gases of combustion from the fire tubes to the stack.

The invention consists in certain novel 35 features of construction and arrangements of parts as hereinafter described and more fully pointed out in the claims.

In the accompanying drawings we have illustrated one complete example, and several 40 modified forms, of steam boilers constructed according to the best modes we have so far devised for the practical application of the principles of our invention, but it will be manifest that other colorable 45 changes and alterations may be made in the shape and sizes of parts as shown in the drawings without departing from the spirit of our invention.

In the drawings: Figure 1 is a vertical 50 longitudinal sectional view of the waist of the boiler and smoke box portion of a locomotive or engine having our invention embodied therein. Fig. 2 is a transverse vertical sectional view taken through the smoke 55 box of the locomotive. Fig. 3 is an enlarged

detail vertical longitudinal sectional view of the boiler with the fire tubes showing the front flue sheet and its connections. Fig. 4 is a diagrammatical view showing a modified arrangement of the front flue sheet. 60 Fig. 5 is another modification of the front flue sheet. Fig. 6 is a further modified form of the front flue sheet and its connections.

In the preferred embodiment of our invention as illustrated in the drawings we 65 have utilized so much of a railroad steam locomotive of standard type as is necessary to illustrate our invention, and we have shown the waist portion 1 of a boiler having the usual steam dome 2, and the main 70 steam pipe or dry pipe 3 located in the steam-space above the longitudinally arranged fire tubes 4 which tubes extend from the fire box (not shown) to the smoke box 5 of the engine, and are fixed in the front flue sheet 75 6 as usual. The smoke box is equipped with the usual stack 7, for receiving the gases of combustion as they pass from the fire tubes through the smoke box, and the exhaust steam nozzle 8 is utilized in connection 80 with the draft pipes 9—9 to facilitate the exit of the gases of combustion. The cylinder saddles are indicated by the numeral 10, the steam pipes leading to the cylinders being indicated by the numbers 11. 85

The front flue sheet is of peculiar construction, and is constructed as follows. The flue sheet is provided with an annular flange or ring 12 which extends circumferentially around the interior of the boiler 90 shell 1, and is secured thereto by bolts or rivets as usual. As clearly seen in Fig. 3, the flue sheet is formed with an offset portion or plate as indicated at 7, and this plate forms the connection between the flange 12 95 and the front flue sheet proper 6. The offsetting of this plate provides an open interior space 13 through which the ends of the fire tube project as they enter the front flue sheet 6, and the offset portion also forms 100 an outer annular space 14 which is of uniform dimension throughout something more than two-thirds of the circumference of the boiler, and at the upper portion the size of the space is increased as at 15. This continuous space formed by the portions 14 and 105 15 is closed by means of a plate 16 which is formed with an annular flange 17 that is attached to the flange 12 of the flue sheet 6, and is cut out in the form or outline of the 110

walls of the space 13, so that the up-turned flange 18 of this plate 16 may be riveted or bolted direct to the flanges of the plate 7.

The steam pipe 3 is formed with a flange 19 which is riveted or bolted to the plate 7, and is passed through a perforation 20 therein. In order to introduce the dry pipe or steam pipe 3 before securing it in position, a flanged cap 21 is provided to fit in and be bolted to the flanges 22 which are struck-up from the plate 16 to form an opening for the reception of this flange plate 21, which is bolted or riveted as shown.

The parts are of sheet metal as usual, and are stamped or struck-up in suitable manner so that they may be produced at a comparatively inexpensive cost, and, of course, all the joints are steam tight, and form steam tight spaces 14 and 15, into which the dry steam pipe 3 leads the steam from the steam dome 2.

By means of the pivoted anchoring bolts or braces 23, which are riveted or bolted at 24 to the boiler, and at 25 are attached to the plate 7, the entire front flue sheet and its accessories are securely held in position, and braced against strain or stress of the boiler construction.

The steam pipes 11 communicate with the interior of the space 14 through openings as 26 (see Fig. 3), and it will be seen that the comparatively dry steam is passed through the steam pipe 3, through the space 15, and reduced space 14 and then through the steam pipes 11 to the cylinders. By this arrangement of the front flue sheet to form the passages for the steam from the steam pipe 3, the presence of steam conductor through the smoke box is eliminated, and an unobstructed and free passage of the gases of combustion is provided for through the smoke box. These results are attained without sacrificing the area of steam heating surface, and the fire tubes are just as great in number as in the locomotives now in use. This structure in the front part of the boiler also braces and reinforces the locomotive, in that the presence of the off-set front flue sheet and the cover plates form an added reinforcement to brace the boiler.

In the modification shown in Fig. 4, the space 15 is retained, but there are provided a pair of legs 14'-14' which extend therefrom and form passages to the steam pipes 11'-11'.

In Fig. 5, the space 15 is retained, but this space 15 is connected with the reduced space 14^a which is annular and extends approximately around the lower half of the boiler shell, by tubes 30-30, and by this arrangement there are provided two separate spaces 15 and 14^a which are connected by the tubes 30 that are located in position to be heated by the passing gases of combustion.

In Fig. 6 a further modification is shown,

wherein the large space 15 is connected to the duplex reduced spaces 14^b-14^b by tubes 31-31, and in this instance we have two smaller superheaters that are connected with the larger space 15 by tubes, and the steam in all three instances is led to the cylinders through the steam pipes 11'.

These modified forms of the invention are constructed along lines similar to the construction of the front flue sheet shown in Figs. 1, 2, and 3, and are merely illustrative modifications of the structure of our front flue sheet, but it will be understood that we contemplate using, and intend to use still further modifications, that are too numerous to illustrate, but which we intend to cover by the following claims.

Having thus fully described our invention, what we claim as new, and desire to secure by Letters Patent, is:

1. The combination with a steam boiler, of a flanged flue sheet having a central off-set portion forming an annular space thereabout, a plate closing said space, the dry pipe communicating with said space, and steam pipes extending from said spaces to supply the cylinders.

2. The combination with a steam boiler, of a front flue sheet having an off-set portion to receive the fire flues, and forming an annular space, a circumferential flange on the flue sheet bounding the outer area of said space, a flanged plate closing the space, a dry pipe communicating with the space, and steam pipes leading therefrom as described.

3. The combination with a steam boiler, of a front flue sheet having an off-set portion to receive the fire flues, and forming a steam space, an annular flange on the flue sheet inclosing said space, a flanged plate closing the space, a dry pipe communicating with the space, steam pipes leading from said space, and braces connecting said flue sheet with the shell of the boiler.

4. The combination with a boiler, of a front flue sheet having a wide flange, and formed with an off-set projecting portion for the fire flues, said projecting portion forming spaces between it and the wide flange of the sheet, a plate closing said space and said spaces adapted to receive dry steam from the steam dome and having outlet steam pipes for the cylinders.

5. The combination with a steam boiler, of a front flue sheet having an outer wide annular flange, an off-set portion, and a closing plate, said off-set portion forming an upper open space for entrance of steam, and also forming restricted passages extending therefrom around the flue shell, and said restricted passages having outlet steam pipes.

6. The combination with a steam boiler, of a front flue sheet having a wide flange and an off-set portion forming therebetween

steam spaces, a plate inclosing said space and attached to said wide flange and off-set portion, a dry steam pipe communicating with said steam space, outlet steam pipes, 5 and an opening in said plate having a flanged cap, to provide for the insertion of said dry steam pipe.

In testimony whereof we affix our signatures in presence of two witnesses.

JOHN FARMER.
MARK E. SHERLAND.
